SPINNING AND TWISTING

Percy Raymond Roadley, Drummondville, Quebec,
Canada, assignor to Celanese Corporation of
America, a corporation of Delaware

Application November 2, 1937, Serial No. 172,325

7 Claims. (Cl. 117—21)

This invention relates to the packaging of yarn or thread from a synthetic yarn spinning device or from any suitable source upon a twisting or repackaging device. This invention relates more particularly to spindle, whorl and throwing-on flyer assemblies that permit of quick throwing-on and prevent injury to operatives or their tools.

An object of the invention is the manufacture of a whorl and spindle assembly that permits of a quick throwing-on of thread to bobbins, spools, quills or other package cores. Another object of the invention is the manufacture of a whorl, spindle and a thread catching element or flyer assembly so arranged and so constructed that the thread can readily and quickly be thrown-on to a package carried thereby and which is non-injurious to employee's hands, their knives or other tools. Other objects of this invention will appear from the following detailed description and drawing.

In the drawing, wherein like reference numerals refer to the same or similar elements in the respective views, there are shown two modifications of my invention.

Fig. 1 is a view, partly in cross-section, showing my invention employed in connection with a spinning device having a cap twisting take-up.

Fig. 2 is a plan view of Fig. 1 with the cap and bobbin removed.

Fig. 3 is a view, partly in section, showing another embodiment of my invention as employed in connection with the ring twisting device, and

Fig. 4 is a detailed view of the throwing-on flyer.

In devices for packaging threads that employ continuously rotating spindles or whorls, or in devices where it is desired to attach the thread to a rotating package, many expedients have been employed to insure a quick and positive throwing-on of the thread which is of particular importance in the spinning of artificial threads which are normally produced at the rate of 200 to 300 or more meters per minute. Prior to this invention, the devices employed for the throwing-on of the thread were injurious to the operator's hands or were costly in installation or in maintenance. Heretofore, at least one of the flanges of the bobbins or spools was equipped with a round headed tack or screw projecting from the periphery thereof. These projections when they hit the fingers of an operator often made a very bad cut. Moreover, the projections being made of metal were also damaging to the knives used by the operator to cut waste thread from the

feed rolls and to threading hooks used in threading the thread through guide eyes, coating devices, etc. To prevent such injury to operators and tools, spools or bobbins having a plurality of notches in their peripheral edges were employed. Although these notches did not cut the fingers of the operators, they nevertheless produced abrasions thereon when the finger came into contact with the same. Often the knives of the operatives were caught by the notches and resulted in damage to the bobbin or to the knife, or both. Other alternatives have also been employed for the throwing-on of the thread. For example, cord or a piece of notched leather was placed under the whorl to effect the throwing-on. These expedients were more or less successful but they have the disadvantage of collecting waste and they need frequent cleaning and renewals.

In accordance with this invention, there is provided a loosely rotating flyer mounted under the package, which flyer is relatively light in weight so that it has little inertia and is adapted to stop immediately and without injuring the finger or tool of an operator when it strikes the same. While the device of the present invention is safe the function of throwing-on is in no way impaired. The device of the present invention is simple and durable and once installed lasts indefinitely.

In accordance with my invention, I form an assembly of spindle, whorl and throwing-on flyer in which the flyer is adapted to stop immediately upon contact with anything heavier than a thread, thus preventing injury to operators and their tools. Furthermore, by employing this invention, no alteration need be made on spools or bobbins. Other details of the invention will appear from the following description made in reference to the drawing.

In Figs. 1 and 2 of the drawing there is shown an assembly, constructed in accordance with this invention, adapted for use on a spinning cabinet of a synthetic thread forming device. In this device, the support for the package or whorl is adapted to rotate continuously even while loading and unloading the whorl. This embodiment of the invention comprises a spindle 1 of any suitable type adapted to be supported by any suitable bolster (not shown) on the spinning machine. The spindle 1 is held stationary and the package is supported and rotated by a whorl 2. The whorl is provided with a cap 3 adapted to overhang the bolster and prevent the lubricating oils from being thrown onto the thread. The cap 3 and rim 4 provide a pulley 5 adapted to retain

a driving belt 6 for rotating the whorl. The groove in pulley 5 may be of any suitable shape depending upon whether the driving means is a cord, belt, V-belt, etc. The section above the rim 4 is turned to form a bearing groove for a flyer 7. The upper edge of the bearing groove terminates in a flange 8 adapted to support a bobbin 9. The bobbin 9 fits loosely over the whorl 2 which extends at least partway through the bobbin. Mounted upon the spindle 1 is a cap 11. The spindle 1 and cap 11 may be of a construction similar to the spindles and caps heretofore used. The bobbin or spool 9 may be any standard bobbin or spool and with the present assembly needs no extra attachments, notches or the like to aid in throwing-on. If desired, the whorl 2 may be a piece of tubing with the pulley 5 and rims 3, 4 and 8 as a separate piece attached thereto or the whorl and pulley may be made in one piece. However, for the purpose of describing this invention and in the appended claims the tube, pulley and flyer bearing are together designated as the whorl.

In operation an empty bobbin 9 is placed upon the whorl 2 and the cap 11 set on spindle 1. The thread 12 is held close to the bottom periphery of the bobbin in which position the flyer 7 attaches the thread and starts it winding upon the bobbin. The flyer 7 is preferably made of spring steel or other resilient material or a resilient material coated with a suitable covering material. The flyer 7 is formed into a substantially circular shape adapted to fit about the turned portion of the whorl, the circular part being smaller than the rim 8 of the whorl. For the purpose of assembly and for renewal of the flyer and to enable the flyer to be placed over the rim 8, the circular part of the flyer is divided into two halves and the two halves are connected by extending U-shaped members 13. At the outer end of the U-shaped members are hooks 14. The hooks 14 are preferably made such that they have a curved outer edge with no points or ends which can contact the fingers of an operator throwing on a thread.

In Fig. 3 is shown a modified form of my invention wherein the spindle, as well as the whorl, is adapted to be rotated. This type of device may be employed in ring twisting and repackaging devices. The assembly comprises a bolster 15 adapted to be attached to a frame (not shown) by means of nuts 16 adapted to rest on top of the frame and nuts 17 adapted to tighten onto the under part of the frame. This may be any standard construction. On the interior of the bolster 15 is the usual dampening and breaking attachments 18. Mounted upon the spindle 1 is

a short whorl 19 having a pulley face 21 for receiving a driving belt. Above the pulley face 21 are two rims 22 and 23 having a groove therebetween. This groove is adapted to receive and retain therein a throwing-on flyer as shown and described in Fig. 4. In operation a quill, bobbin or other type core is slipped on the upper end of the spindle 1 and rests upon a rim 23 which acts as the driving means for a rotating package core. The operation of throwing-on is the same as that described with reference to Fig. 1.

It is to be understood that the foregoing detailed description is merely given by way of illustration and that many variations may be made therein without departing from the spirit of my invention.

Having described my invention, what I desire to secure by Letters Patent is:

1. In a thread packaging device employing a rotating package the combination of a spindle, a whorl and a throwing-on flyer loosely mounted on the whorl.

2. In a thread packaging device employing a rotating package the combination of a spindle, a whorl having a spooled-out section and a throwing-on flyer mounted for free rotation in the spooled-out section.

3. In a thread packaging device employing a rotating package the combination of a spindle, a whorl and a throwing-on flyer comprising two semi-circular members adapted to loosely fit on the whorl.

4. In a thread packaging device employing a rotating package the combination of a spindle, a whorl and a throwing-on flyer comprising two semi-circular members adapted to loosely fit on the whorl, said members being connected through U-shaped members.

5. In a thread packaging device employing a rotating package the combination of a spindle, a whorl and a throwing-on flyer comprising two semi-circular members adapted to loosely fit on the whorl, said members being connected through U-shaped members having thread engaging hooks.

6. In a thread packaging device adapted for use on a synthetic thread forming cabinet employing a continuously rotating take-up package the combination of a spindle, a whorl and a throwing-on flyer loosely mounted on the whorl.

7. In a thread packaging device adapted for use on a synthetic thread forming cabinet employing a continuously rotating take-up package the combination of a stationary spindle, a whorl and a throwing-on flyer loosely mounted on the whorl.

PERCY RAYMOND ROADLEY.
